UNITED STATES PATENT OFFICE.

LOUIS STEINBERGER, OF BROOKLYN, NEW YORK.

STRAIN INSULATOR.

Substitute and continuation of application Serial No. 264,147, filed November 26, 1918. This application filed April 3, 1920. Serial No. 370,973.

To all whom it may concern:

Be it known that I, LOUIS STEINBERGER, a citizen of the United States, and a resident of the borough of Brooklyn, city and State

5 of New York, have invented certain new and useful Improvements in Strain Insulators, of which the following is a specification.

My invention relates to strain insulators, 10 one of the objects of which is to provide an insulating body portion which is at all times detachable from the strain members of the insulator.

Another object is to so construct the strain 15 insulator that the body of insulating material and the strain members may be rapidly and easily assembled and disassembled.

Other objects will appear from the subjoined specification and claims.

20 This application is filed as a substitute and continuation of my application Serial No. 264,147 filed November 26, 1918.

In the drawings in which the same reference character indicates the same part in 25 the several views:

Fig. 1 is a vertical section showing an insulator assembled embodying my invention.

Fig. 2 is a side elevation of the same viewed in the direction of the arrow in 30 Fig. 1.

Fig. 3 is a plan view of the insulator body, which body is similar in appearance viewed from either end.

The strain members A and A' are duplicates of each other, as clearly shown in the drawing, in which the bridge portions consist of rings 10 and 10' connected respectively to the leg portions thereof. The leg portions 12 and 13 of the strain member A and 12' and 13' of the strain member A' are connected respectively to the rings 10 and 10' by the elbows 16, 17 and 16', 17', the elbows being connected to the rings at points diametrically opposite each other, the respective leg portions extending vertically therefrom. Each of the strain members is made up of two parts, the parts 30 and 31 of the respective strain members being screwthreaded at the ends of the respective leg portions. Likewise the other separable parts 30' and 31' of the respective strain members are yoke shape and are provided with projecting ends 34, 35 and 34' and 35' which coincide with the screwthreaded ends 50 respectively of the leg portions 12 and 13 and 12' and 13' so that the two portions 30

and 31 and 30' and 31' of the respective strain members are secured together by engaging the nuts or sleeves 40 and 41, 40' and 41'.

60 In forming the body of insulating material I mold it into the shape shown in the drawing, in which there are two circular recesses 50 and 51 one in each face thereby permitting the seating of the rings forming 65 the bridge portions of the strain members. Extending vertically and radially from these circular recesses are grooves 52, 53, 54 and 55 for receiving the elbow portions of the strain members, and grooves 60, 61, 62 70 and 63 for receiving the leg portions of the strain members.

A series of circular grooves 70 and ridges 71 also are formed in the side of the insulator member for the purpose of increasing 75 the surface area thereof.

The grooves or corrugations above described, which are provided for the reception of portions of the strain members, may be either round, square or other suitable 80 shape to fit the particular shape of the strain members.

In the bottom of the grooves in which the ring portions of the strain members are seated, I provide resilient or yielding 85 washers 80 and 81 so as to take up the mechanical strains and stresses which are imposed upon the insulator body by the strain members.

In assembling the insulator the body B 90 is fitted to one strain member so that the projecting leg members are brought into line with the oppositely disposed grooves in the sides of the insulator body, and the insulator body is thus permitted to seat itself 95 upon the elbows and ring shaped portion of the strain member. The other strain member is then lowered into place by positioning the vertical legs thereof in the other pair of vertical grooves in the sides of the insulator 100 body B, and lowered into position as will be clearly understood. The other separable portions of the strain members 30' and 31' are then placed in respective positions and secured to the projecting legs of the complementary strain member by the respective sleeve nuts.

105 As will be understood from the above description and illustration in the drawing, the insulator body and the interlocked strain members may be very quickly assembled or disassembled, and new bodies of insulating

material may be substituted for the old ones very quickly and readily.

The insulator may be made of any suitable moldable insulating material such as that known in the art as "electrose," or it may be made of porcelain, glass or other vitreous or fireproof insulating material.

As changes of construction could be made within the scope of my invention, it is intended that all matter contained in the above description or shown in the accompanying drawings shall be interpreted as illustrative and not in a limiting sense.

Having now described my invention, what I claim as new and desire to secure by Letters Patent is:

1. In a device of the kind described, a body of insulating material provided with circular seats in the opposite faces thereof for the reception respectively of the bridge portions of strain members and with vertically disposed grooves in the side to receive the leg portions of said strain members, said grooves extending from end to end of the insulator body, said vertically disposed grooves being arranged in pairs, each

pair being respectively connected by grooves to one of said oppositely disposed circular seats.

2. In a device of the kind described, a body of insulating material provided with circular seats in the opposite faces thereof for the reception respectively of the bridge portions of strain members and with vertically disposed grooves in the side to receive the leg portions of said strain members, said vertically disposed grooves being arranged in pairs and extending from end to end of the insulator body, each pair being respectively connected to the circular seats by radially disposed grooves in the faces of the insulator body, said radially disposed grooves being situated in different planes from the horizontal planes of the circular seats with which they are connected.

In witness whereof I have hereunto set my hand at the borough of Manhattan, city and State of New York, this second day of April, 1920.

LOUIS STEINBERGER.

In presence of—

ISABEL R. FLETCHER.
